UNITED STATES PATENT OFFICE

RUTH ANDREW DEAN, OF BOSTON, MASSACHUSETTS, ASSIGNOR TO HARRINGTON & KING PERFORATING COMPANY, OF CHICAGO, ILLINOIS, A CORPORATION OF ILLINOIS

DESIGN FOR A GRILLE PANEL

Application filed August 31, 1932. Serial No. 44,731. Term of patent 14 years.

To all whom it may concern:

Be it known that I, RUTH ANDREW DEAN, a citizen of the United States, residing at Boston, in the county of Suffolk and State of Massachusetts, have invented a new, original, and ornamental Design for a Grille Panel, of which the following is a specification, reference being had to the accompanying drawing, forming a part thereof.

In the drawing:

The figure is a face view of a section of a grille panel showing my new design which is to be repeated as often as desired in the relation shown.

I claim:

The ornamental design for a grille panel substantially as shown and described.

RUTH ANDREW DEAN.
